UNITED STATES PATENT OFFICE.

SAMUEL SOLODAR, OF NEW YORK, N. Y.

ALARM SYSTEM.

Application filed November 1, 1924. Serial No. 747,259.

This invention relates to alarm systems, and particularly to alarm systems for business places and the like, by which the assistance of police or firemen may be summoned in the event of need. It is especially applicable to the calling of police in cases of hold-ups in business places.

An object of the invention is to provide an improved alarm system and parts thereon which may be set in operation by the proprietor or his assistant in a manner likely to be unobserved by a bandit, which may be set in operation without the use of hands or feet, and which is relatively simple, effective and inexpensive. A further object is to provide an alarm system the operativeness of which may be tested whenever desired without the summoning of police or firemen. A further object is to provide an alarm system which will audibly and visibly summon aid and which will also frighten the bandit or unnerve him. A further object is to provide a system for accomplishing the above objects in which the parts will not be likely to get out of order.

Various other objects and advantages will be apparent from the following description of an embodiment of the invention, and the novel features will be pointed out hereinafter in the appended claims.

In the accompanying drawings, Figure 1 is a sectional plan of a business place, such as a store, in which an alarm system has been incorporated in accordance with this invention.

Fig. 2 is a sectional plan through a portion of the apparatus utilized in the system and illustrating the wiring connections therefor.

Fig. 3 is a sectional elevation of a portion of the same apparatus, the section being taken approximately along the line 3—3 of Fig. 2 and

Fig. 4 is a sectional elevation through one part of the apparatus shown generally in Fig. 2.

In the illustrated embodiment of the invention, the business place is located within the side walls 1 and 2, the rear end wall 3 and the front or show window 4, it being understood that the usual entrance way 5 is closed by the usual door 6 similar to the door generally used in shops or places of business. Within the shop the counters 7 may be arranged in any desired order, and back of the counters there is a false wall or shelv-

ing arrangement 8 upon and in which the goods to be sold may be stored for display purposes or for the convenience of the sales people. The business place may also be provided with a rear room 9 from which a stairway 10 may lead to the basement. Within the business place, in any suitable location such as within a compartment 11, I have located a part of the apparatus utilized in the system. In this compartment I provide a suitable tank or container 12 for a supply of compressed air or other fluid, and a conduit 13 leads from the upper wall thereof, the conduit having a T-shaped upper end 14. In one arm 15 of the T-shaped end I provide suitable valve mechanism 16 similar to that employed in pneumatic tires, through which the air or fluid may be conducted into the tank or container 12 under compression. The end of the branch 15, which is open, may be normally closed by a valve cap 17 similar to the closure commonly employed for valve stems of pneumatic tires. A sleeve 18 may be threaded over the other arm 19 of the T-shaped head 14.

Within the branch or arm 19 of the T-shaped head, which is tubular, I provide suitable valve mechanism 20 similar to the mechanism 16 which normally prevents egress of the compressed air from the conduit or pipe 13. This valve mechanism, however, has a stem 21, which when depressed will cause an opening of the valve mechanism 20 and allow the air or other compressed fluid to pass through the branch 19. In the outer end of the sleeve 18 I mount for reciprocation a plunger 22 which upon its outer end is provided with an operating head or button 23 and near its inner end with a conical valve element or shoulder 24 which co-operates with a conical valve seat at the junction between the inner end wall of the sleeve and the passage into the plunger which is mounted for reciprocation.

The plunger in the portion 25 within the passage in the sleeve and immediately adjoining the conical portion 24 is reduced in diameter so that when the plunger is pushed inwardly to unseat the conical portion 24, communication will be established between the interior of the sleeve and the passage in which the plunger reciprocates for a short distance. The sleeve 18 is provided with a branch passage 26 which communicates with the passage in which the plunger 22 reciprocates at the point occupied by the reduced

portion 25 of the plunger so that when the plunger is pushed inwardly communication will be established between the interior of the sleeve and the branch passage.

5 The extreme inner end of the plunger is of smaller diameter than the base end of the conical portion 24 and carries a pair of washers or gaskets 27 and 28 which are of larger diameter than the base end of the
10 conical portion 24, and which abut against the inner end wall of the sleeve when the conical portion is seated in the passage occupied by the plunger. A shell 29 is fitted over the gasket 28 and has a reduced hollow end extending therefrom and terminating in close proximity to the outer end of the valve stem 21. Thus when the plunger 22 is pushed inwardly the conical portion 24 will force the washers or gaskets 27 and 28 inwardly and through them operate the shell 29 to depress the valve stem 21 so that communication will be established directly from the interior of the tank 12 to the branch passage 26 of the sleeve 18.
15
20 25 A helical spring 30 may be interposed under compression between the outer end of the branch arm 19 of the T-head 14 and the shell 29 so as normally and yieldingly to hold the gaskets 27 and 28 against the end wall of the sleeve and prevent communication with the passage in which the plunger reciprocates. Within the tubular extension 29 and the extreme inner end of the plunger another cylindrical spring 31 is interposed under compression so that even after the gasket 27 is forced against the inner wall of the sleeve, the spring 31 will further shift the plunger to seat the conical portion and provide a double closure for the passage in which the plunger reciprocates.
30
35
40

45 A lever arm 32 is pivoted at 33 for movement to carry the free end of the lever 32 into engagement with the button 23 of the plunger and by further movement force the plunger inwardly to open communication between the tank 12 and the branch passage 26 of the sleeve 18. A suitable spring device 34 may be provided for yieldingly forcing the lever arm 32 in a direction to force the plunger inwardly when the lever arm is released. A detent arm 35 is carried by the lever arm 32 and rests upon the shoulder 36 of an armature 37, the latter being pivoted at 38 for movement in a direction to withdraw the shoulder from the end of the detent arm 35. When this release or withdrawal is effected the lever arm 32 will be released to effect an opening of the valve mechanism in the sleeve 18. The armature 55 is normally held retracted by a spring 39 and is drawn in a direction to release the arm 35 by an electro-magnet 40 which is energized at the instant of alarm by mechanism which will be described presently.

60 A conduit 41, normally a continuation of

45 A conduit 41, normally a continuation of

the passage 26 (see Fig. 2) leads to the exterior of the shop at the front and carries at its outer end a police whistle or other fluid operated device 42. Within the conduit 41 a transversely reciprocating valve element 43 is provided, the passage 44 of the valve element being arranged to continue the communication between the passage 26 and the conduit when the valve element is in one operative position. A helical spring 45 in a tubular enlargement 46 of the conduit 41 surrounds a stem 47 of the valve element and by reason of its compression between the end of the tubular extension 46 and the shoulder of the valve element serves to force the valve element in a direction to carry the bore 44 into alignment with the passage 26. Nuts 48 upon the end of the stem 47 which projects through the tubular extension 46 limit this movement of the valve element under the action of the spring 45. The valve element 43 has a tubular extension 49 which serves as an operating member through which the valve element may be shifted against the action of its spring to carry the door 44 out of alignment with the passage 26 and thus shut off communication between it and the conduit 41. The valve element and handle 49 are provided with a branch test passage 50 which opens laterally from the valve element at a point such that when the valve element is shifted inwardly to shut off communication with the conduit 41 it will move into alignment with the passage 26.

A battery or other source of current 51 is provided at any suitable part of the shop and from this battery a wire 52 leads to a plurality of push buttons or other switches 53 which are connected in parallel to one another and provided at various suitable points around the interior of the store or business place at points convenient for operation, preferably at such heights that they may be operated into closed position by the backing of a person into the same. 100 105 110 115

The wire 52 is also connected by a wire 54 to a contact arm 55 carried by the handle 49 of the valve element 43 for movement into engagement with a contact spring 56 whenever the valve element is operated to 115 shut off communication with the conduit 41 leading to the police whistle and connect the passage 26 to the passage 50 in the valve element. A second contact spring 57 is mounted in the path of a contact arm 58. 120 Contact arm 58 is carried by the valve element through an insulating bushing 59 and will engage the spring 57 at the same time that the contact arm 55 engages with the spring 56. Another spring contact 60 is arranged to be engaged by the contact arm 58 at the same time that the spring 57 is engaged and as a result the arm 58 will serve 125 to bridge these two spring contacts 57 and 60.

When the valve element 43 is in its nor- 130

mal position shown in Fig. 2 the contact arm 58 will engage with a bridge 2 spring contacts 61 and 62, this bridging engagement being broken as soon as the valve element 5 is operated to shut off communication between the passage 26 and the police whistle through conduit 41. The springs 60 and 62 are connected together by a wire 63 and through it to a binding post 64 (see Figs. 2 and 3) leading to one side of the electro-magnet 40; for instance, see Fig. 3. The other terminal of the electro-magnet 40 has its binding post 65 (see Fig. 2) which is connected by wire 66 to the other sides of all of the switches 53 and also to the spring contact 56. The contact spring 61 is connected by a wire 67 to a cartridge exploding device 68 shown generally in Fig. 2 and in detail in Fig. 4, the cartridge exploding device also being connected by a wire 69 to the other side of the battery. A wire 70 also connects the wire 69 to the spring contact 57. The operation of the circuits thus described will be explained later.

The cartridge exploding device 68 is enclosed within a housing having a cover 71. Within the housing the blank cartridge 72 is supported in a suitable well 73 with its head 74 within the path of a hammer point 75 that is provided upon the end of the hammer lever 76. The lever 76 is pivoted at 77 so that when released it will fall by gravity and assisted by the spring 78 so as to drive the point 75 against the cartridge head 74 and explode the cartridge. The lever 76 is normally held in its upper inoperative position by an auxiliary lever 79 pivoted at 80 and the lever 79 is held in upper position by a detent lever 81 which is pivoted at 82. The lower end of the lever 81 is provided with an armature 83 which may be acted upon by a magnet 84 so that when the magnet is energized the lever 81 will be removed from its propping engagement with the auxiliary lever 79. A magnet 84 is connected to the wires 67 and 69 shown diagrammatically in Fig. 2 and hereinbefore explained. Within the path of the lever 32 which operates the plunger 22 I provide a flasher switch 85. This flasher switch is controlled or rendered operative by a spring retracted pin or plunger 86 which is engaged and operated by the lever 32 when the lever 22 is released to actuate the plunger. Circuit wires 87 and 88 lead from the plunger 85 to a suitable source of current, one of the wires such as 87 including therein a suitable electric light 89 which is disposed outside of the shop front as shown in Fig. 1 and diagrammatically in Fig. 2. When the valve mechanism from the tank 12 is operated to cause an actuation of the whistle the light 89 will be simultaneously lighted and flashed by means of the flasher.

The valve mechanism leading from the tank 12 and the magnet 40 and parts controlled thereby may be enclosed by a suitable dome 90 which fits over the upper end of the tank 12, and a chain 91 connected at 70 one end to the lever 32 passes through an aperture 92 in the dome 90 and through an aperture 93 in a housing wall surrounding the tank so as to be accessible for manipulation to withdraw the lever until the detent arm 35 is again latched in its upper position upon the shoulder of the armature 37.

In the operation or use of the device it is assembled in the manner illustrated and the switches 53 are arranged at convenient points around the shop so as to be either manually operated by one's hands or feet, or preferably at suitable elevations where one may back into the same when confronted by a bandit. In the event of a hold-up the salesman may back into or operate one of the switches 53, which will close the circuit from the battery chamber traced as follows: from the battery 51 through wire 52, switch 53, wire 66, magnet 40, wire 63, spring contact 62, contact arm 58, contact spring 61, wire 67, cartridge exploding device 68, wire 69, back to battery. When this circuit is completed the cartridge exploding device will be operated to cause an explosion of the cartridge by reason of the withdrawal of the lever 81, thus permitting the fall of the hammer point 75. At the same time the magnet 40 will withdraw the armature 37 to release the detent arm 75, and the lever 32 under the action of the spring 34 will thereupon operate the plunger 22 to open the valve mechanism 20 and the valve mechanism provided in the interior of the sleeve 18. By reason of this operation of the plunger 22 the compressed air from the tank 12 will pass to the police whistle located upon the exterior of the shop and will audibly indicate to the policeman on the beat that his assistance is urgently needed at this particular place of business.

The sounding of the police whistle and the simultaneous explosion of the blank cartridge will have a material part in the frightening of the bandit, so disconcerting or unnerving him that he will probably withdraw without proceeding further with the hold-up; but in the event that such is not the case, the signal will of course continue and summon the policeman's aid.

At the same time that the lever 32 moves to start the operation of the police whistle, it will also engage the plunger pin 86 and cause an illumination and flashing of the light 89 on the front of the shop by reason of the action of the flasher 85. This flashing of the light 89 will indicate to the policeman hastening to the aid of the shop-keeper the exact location of the hold-up, which will avoid delay in the arrival of

police assistance. When help has arrived and the operation of the signal system is no longer desired, it is necessary merely to pull the chain 91, which will by its release of the plunger 22 allow the valve mechanism to return to normal position and shut off the supply of compressed air to the whistle. At the same time the plunger 86 of the flasher device will be released so as to shut off the light 89.

In order that the device may be tested from time to time to insure its working condition, it is necessary only to ascertain the working condition by shifting the valve element 43 against the action of the spring 45. This will shut off the supply of fluid to the police whistle and will connect the branch passage 50 to the passage 26. During this movement of the valve element 43 the contact arm 55 will be carried into engagement with the contact spring 56 to close a circuit between the wires 54 and 66 which are in parallel with the switches 53, thereby initiating the operation of the mechanism. However, at the initial movement of the valve element and before the arm 55 engages the spring 56 to initiate the movement, the contact arm 58 will move from its bridging engagement between the contact springs 61 and 62 and open the circuit between the cartridge exploding device and the wire 63. When the valve element has been shifted to its extreme test position the contact arm 58 bridges the contact springs 57 and 60 at the same time that the contact arm 55 engages contact spring 56 to initiate the alarm operation. The arm 58 thus connects the wire 63 to the wire 70, which completes the circuit back to the battery without passing through the cartridge exploding device, the latter circuit having been opened at the contact spring 61. During this operation the light 89 will flash as before and the compressed air will pass through the passage 50 and by its rush indicate that it is in proper operating condition; the bore 44 of the valve element 43 being out of alignment with the passage 26, the police whistle of course will not be operated. After the valve element has been released, or simultaneously with the release, the chain 91 may be pulled to restore the control lever 32 to normal position.

It will be observed from the foregoing that a very effective and practical alarm system has been devised and that its operative condition may be determined at any time without causing excitement in the vicinity of the store. By removing the cap 17 an air pump may be connected to the T-head 14 and a supply of compressed air placed in the tank 12 ready for use whenever desired.

While the switches 53 have been illustrated as manually operated switches, it will be understood that if desired they may be

controlled by a thermostat or fusible plug, so that in the event of fire in the premises, the switch may be operated by the increase of temperature in said premises to summon aid of the fire department.

It will also be understood that various changes in the details which have been herein described and illustrated in order that the nature of the invention may be understood, may be made by those skilled in the art within the principle and scope of the invention as set forth in the appended claims.

I claim:

1. In an alarm system for the protection of buildings, a container for a compressed fluid, an audible signal device operable by compressed air, a conduit connecting said device and container and having therein a valve, normally spring pressed into closed position to prevent operation of the signal device, said valve having a projecting operating stem, electromagnetically controlled means for operating the valve to open position, an electric light, an explosion device, means for controlling the explosion device, said light being controlled by electromagnetically controlled means, a master circuit for controlling the explosion device controlling means and said electromagnetically controlled means, a second valve in the conduit between the audible signal device and the other valve and spring pressed to open position, the movable member of the second valve having a by-pass conduit movable into communication with the container through the first valve when it shuts off communication from the container to the audible signal device, and means operable by the second valve when moved to cut off the audible signal device for changing the condition of the master circuit to cause an operation of the first valve and light and placing the exploding controlling means in a condition to prevent operation of the exploding device whereby the operativeness of the device may be readily determined without operation of the audible signal device or said explosion device.

2. In an alarm system for the protection of buildings, a container for a compressed fluid, an audible signal device operable by compressed air, a conduit connecting said device and container and having therein a valve, normally spring pressed into closed position to prevent operation of the signal device, said valve having a projecting operating stem, electromagnetically controlled means for operating the valve to open position, an electric light, an explosion device, means for controlling the explosion device, said light being controlled by electromagnetically controlled means, a master circuit for controlling the explosion device controlling means and said electromagnetically controlled means, a second valve in the conduit between the audible signal device and the

other valve and spring pressed to open position, the movable member of the second valve having a by-pass conduit movable into communication with the container through 5 the first valve when it shuts off communication from the container to the audible signal device, means operable by the second valve when moved to cut off the audible signal device for changing the condition of the 10 master circuit to cause an operation of the first valve and light and placing the exploding controlling means in a condition to prevent operation of the exploding device

whereby the operativeness of the device may be readily determined without operation of the audible signal device or said explosion device, and manually controlled means for restoring the electromagnetically controlled means to a condition releasing the first valve whenever cessation of operation of the audible signal and extinguishment of the light 15 are desired.

In testimony whereof I have hereunto set my hand.

SAMUEL SOLODAR.
